Z. Pangborn.

Building.

No 19,445.

Patented Feb 27, 1855.

UNITED STATES PATENT OFFICE.

Z. PANGBORN, OF ALGONAC, MICHIGAN.

CONSTRUCTION OF VESSELS.

Specification of Letters Patent No. 12,445, dated February 27, 1855.

To all whom it may concern:

Be it known that I, ZADOC PANGBORN, of Algonac, in the county of Sinclair and State of Michigan, have invented an Improvement in Construction of Vessels to Prevent Them From Sinking, and that the following is a full, clear, and exact description of the principle or character which distinguishes it from all other things before known and of the usual manner of making, modifying, and using the same, reference being had to the accompanying drawings, of which—

Figure 1 is a plan of the frame work of the boat showing a top view of the air chambers. Fig. 2, is a side elevation of the same. Fig. 3, is a cross section through the line α , α , showing one of the ribs of the vessel. Fig. 4 is a detached view showing the separate tanks with the ends left open.

My invention consists in a certain construction of the hulls of vessels whereby I provide the means of preventing them from sinking in the event of accidents from explosion, fire, storm, collision, snags, reefs or any other cause and at the same time adding to the strength of the vessels hull. I am aware that tanks have been used in various ways for buoying up boats and vessels and I do not lay claim to such devices except under the arrangement and construction herein set forth. Each rib of the hull a , a , etc., is bifurcated or continued in two parts to a sufficient height above the lower deck; these parts joining at the top so as to leave an angular or somewhat lozenge shaped space b , b and these spaces increasing in size and height toward midships fore and aft, so as to form an arch c , c which gives great

strength to the hull, being a security against hogging, stiffening the boat and making it less liable to injury from collision. These spaces b , b may have the cross ties d , d , in part of them or in all, and the whole when properly sheathed will form buoyant air vessels of great capacity. In order however to guard against fire which would destroy them, I make the inner lining of these spaces b , b , of sheet metal so that the metal tanks will in such case be preserved and should the fire be in the upper works the vessel may be scuttled fore and aft or both as the case may be and the fire checked and the vessel still floating may be pumped out and recovered. In order to render this device more safe in the event of damage to any part of the vessel I divide the inner metal tanks so as to have separate compartments as shown in Fig. 4—at e , e . In the case of armed vessels the requisite number of port holes must be left and owing to the greater depth required in this structure for port holes, they must be made flaring either inward or outward as the case may be. The sheathing may be of iron or wood whichever may be thought best.

What I claim as my invention is—

The arrangement of tanks constructed as above set forth the same consisting in the extension and bifurcation of the ribs of vessels hulls so as to form an arched series of tanks or receptacles for tanks in the manner and for the purposes herein set forth.

Z. PANGBORN.
